UNITED STATES PATENT OFFICE.

CHARLES G. ASHLEY, OF CHICAGO, ILLINOIS, ASSIGNOR TO GENERAL ENGINEERING AND CONSTRUCTION COMPANY, LIMITED, OF TORONTO, CANADA, A CORPORATION OF ONTARIO, CANADA.

PRINTING-TELEGRAPH ALPHABET.

1,135,344.

Specification of Letters Patent. Patented Apr. 13, 1915.

Application filed June 20, 1911. Serial No. 634,199.

To all whom it may concern:

Be it known that I, CHARLES G. ASHLEY, a citizen of the United States of America, and a resident of Chicago, county of Cook, 5 and State of Illinois, have invented a new and useful Improvement in Printing-Telegraph Alphabets, of which the following is a specification.

My invention relates to a Roman alphabet, the characters of which are built up 10 from predetermined combinations of impressions from four elemental component types, the impressions being potentially, periodically recurrent considered lineally 15 along the line of writing.

My invention finds its chief application in automatic printing telegraph systems in which a plurality of component types are 20 electro-magnetically controlled and operated by current impulses over line conductors, the selection being consummated by means of a perforated transmitting tape. In the practical application of such systems it has 25 been proven that under all line conditions and especially under adverse line conditions, a higher transmission efficiency is attained by the use of an alternating current. The use of an alternating current, however, imposes as a requirement for high speed transmission 30 that a maximum number of the alternations in a current of a definite frequency shall be utilized to imprint predetermined types, in order that the maximum imprinting possibilities of a current of a 35 definite frequency may be realized.

My invention has as its object to provide a directly readable Roman alphabet the characters of which are imprinted from impressions of component types available for 40 selection only in cyclic order. I accomplish this and other desiderata by utilizing a design of character that is built up from a number of predetermined impressions from component type faces, the impressions necessary to complete a character being selected 45 from a potentially periodically recurrent series of single impressions from all of the component types.

In the figures which accompany and form 50 a part of this specification and in which like numerals designate corresponding parts throughout: Figure 1 is an enlarged plan view of the four component type faces arranged in the form of a printing telegraph 55 printing symbol. Fig. 2 is a plan view of a

record of the impressions of all of the type faces such as would result from utilizing all of the alternations of an alternating current for imprinting purposes. Fig. 3 is a view of my improved alphabet together with the 60 numerals from 0 to 9 inclusive, so spaced with regard to Fig. 2 as to illustrate the principle of its design.

As there are numerous methods and means known in the printing telegraph art 65 for selectively operating types having faces similar to those shown in Fig. 1, it is not deemed necessary in this disclosure to illustrate any definite arrangement of apparatus or circuits for the operation of the types 70 shown. Assuming therefore that the type faces as shown in Fig. 1 are maintained in such relation to a recording surface that each may record an impression thereon, that the recording surface be moved under the 75 type as viewed in Fig. 1 from right to left at a speed which is commensurate with the alternations of the alternating currents used, and that the distance between any two maximum current values is further commensurate 80 with the spacing between the types as indicated by the spaced inclined lines in Fig. 1. Assuming further that type face 4 is operated by a positive potential, then from the foregoing it follows that type face 85 3 is operated by the next succeeding negative impulse, type face 2 is operated by the next succeeding positive impulse while type face 1 is operated by the next succeeding negative impulse. Therefore, if an alter- 90 nating current of a predetermined frequency be placed through the controlling magnets of the types 4, 3, 2 and 1, they will be imprinted in cyclic distribution on the receiving tape and the resultant record will be a 95 continuous lattice as shown in Fig. 2.

Referring again to Fig. 1 it will be noted that type faces 1 and 3 are each in width equal to the distance between any five of the spaced lines through the symbol while type 100 face 2 is equal in length to the distance between any four of these spaced lines. Type face 3 is separated from type face 4 by the distance between any two spaced lines, while type face 2 is separated from type face 3 by 105 the distance between any three spaced lines. Type face 1 is maintained a distance from type face 2 equal to the distance between any two spaced lines.

If now a transmitting tape be perforated 110

- with a predetermined spacing of perforations, it will be noted that it will be possible to select from the operating alternating current impulses of predetermined potential to operate predetermined type faces to imprint their impressions in proper relation to previous imprints in the course of their potential recurrence to form legible characters.
- The letter "A" is built up and recorded by
- 10 the use of an alternating operating current as follows: The first positive current maximum imprints type face 4, the record tape moves after such imprint from right to left a distance equal to that between any two spaced lines on the symbol Fig. 1 or one tape interval while the current changes in value from positive maximum to negative maximum at which time type face 3 is in a potential condition of operation, but
- 15 through the predetermined spacing of the perforations in the transmitting tape the impulse for its operation is omitted and the type face is not recorded; the recording tape continues and moves one tape interval while
- 20 the current changes from negative maximum to positive maximum at which time type face 2 is in a potential condition of operation but through the predetermined grouping of perforations in the transmitting tape the perforation for the operation of type face 2 is omitted and its imprint is not recorded. The record tape moves one tape interval while the current changes from positive maximum to negative maximum at
- 25 which time type face 1 is in a potential condition of operation but its imprint is omitted through the predetermined grouping of the perforations in the transmitting tape. The record tape again moves one tape interval while the current changes in value from negative maximum to positive maximum at which time type face 4 is again imprinted and as the record tape has moved since the previous imprinting of type face
- 30 4 a distance of four tape units, this second impression is displaced from the first impression a distance of four tape units or the width of a complete normal character. The tape now moves one tape unit while the current changes in value from positive maximum to negative maximum at which time type face 3 is again in a potential condition of operation but its imprint is omitted. The tape again moves one tape interval while the
- 35 current changes in value from negative maximum to positive maximum at which time type face 2 is imprinted with its left extremity abutting the first imprint of type face 4 and its right extremity separated
- 40 from the last impression of type face 4 by one tape interval. The record tape now moves one more tape interval while the current changes in value from positive maxi-

mum to negative maximum at which time type face 1 is imprinted with its vertical leg coinciding with the upper portion of the first imprint of type face 4 and the right extremity of its horizontal leg abutting the last imprint of type face 4 to form the letter "A".

Thus any of the characters of the alphabet and the figures from 0 to 9 as illustrated in Fig. 3 may be imprinted by any transmitting tape which is provided with groupings of perforations which select from the potentially cyclic recurrent impressions a predetermined group of impressions.

It will be observed that with my improved design of alphabetical characters, I attain through the regularity of the operating impulses, a cyclic distribution of the impressions which permits the use of an alternating current for transmission; from the particular design of character, a pleasing and extremely legible alphabet and further, a minimum length of receiving tape for a given message.

I produce an alphabet in which the successive letters are disconnected from each other: I produce an E having only the width of a normal letter. As the letter E is used more frequently than any other letter of the alphabet, the minimizing of its space economizes both tape length and transmission time.

Having thus described my invention what I claim as new and desire to secure by United States Letters Patent is as follows:

In a Roman alphabet for printing telegraph systems, a recurrent combination of elemental lines composed of lower horizontal and lower half vertical abutting at the right end of the said horizontal, said two elemental lines appearing always in combination and appearing in the letter "E"; a full vertical occurring in many characters and appearing in the letter "E" in registry with the left end of the lower horizontal; a top horizontal and a middle horizontal, the middle horizontal having a length less than said bottom horizontal and registering at its left end with the full vertical of the letter "E" and extending at its right end to a point at the left of the half vertical of the letter "E" whereby said half vertical and said middle horizontal are disjoined and said letter "E" is rendered legible as such.

Signed by me at Toronto, county of York and Province of Ontario, in the presence of two witnesses.

CHARLES G. ASHLEY.
